Filed Dec. 17, 1964, Ser. No. 83,269

Term of patent 14 years

(Cl. D52—1)

FIG.1

FIG.3

FIG.2

FIG.4

FIG. 1 is a front elevational view of a computer, showing my new design.

FIG. 2 is a view in side elevation.

FIG. 3 is an end view.

FIG. 4 is a rear view thereof.

The undisclosed side of the computer is substantially the same in appearance as the side shown.

The broken line portion in FIGURE 1, represents memo or data paper and is shown for illustrative purposes only.

The dominant features of the design reside in the portions shown in full lines (MPEP, 1503.02, par. 3).

I claim:

The ornamental design for a computer, substantially as shown and described.
